UNITED STATES PATENT OFFICE.

JOSEPH B. MORRISON AND JOHN W. CALLISON, OF FORT MADISON, IOWA,
ASSIGNORS TO MORRISON MANUFACTURING COMPANY, OF FORT
MADISON, IOWA, A FIRM.

CLEVIS.

SPECIFICATION forming part of Letters Patent No. 779,094, dated January 3, 1905.

Application filed December 26, 1903. Serial No. 186,688.

To all whom it may concern:

Be it known that we, JOSEPH B. MORRISON and JOHN W. CALLISON, citizens of the United States, residing at Fort Madison, Iowa, have 5 invented certain new and useful Improvements in Clevises, of which the following is a specification.

This invention relates to clevises, and particularly to that class of clevises adapted to 10 be attached to the forward end of a plow-beam, and has for its object to provide a clevis of this character adapted to be attached to the end of the plow-beam by means of a connection having in effect a universal or 15 gimbal joint movement the movements of which are regulated and controlled by the operator through hand-levers; to provide a clevis of the character referred to which can be adjusted as to all of its movements by the use 20 of said levers without stopping the plow; to provide, in connection with a clevis adapted to be moved by means of hand-levers to regulate the line of draft, a socket for receiving 25 the stem of a pole or tongue when the use of such is desired, and in general to provide a compact, cheap, and practical clevis of the character referred to.

The invention will be understood from the following description, reference being had to 30 the accompanying drawings, in which—

Figure 1 is a perspective view of a clevis embodying the invention and attached to the end of a plow-beam. Fig. 2 is a top plan view of the same, the regulating-levers being 35 shown in section. Fig. 3 is a view similar to Fig. 1, showing the clevis moved downwardly upon its horizontal axis. Fig. 4 is a view similar to Fig. 2, showing the clevis moved laterally. Fig. 5 is a detail view of the joint 40 or hinge block, and Fig. 6 is a detail showing the clevis-frame.

Referring to the drawings, 1 designates the end of a plow-beam, having mounted upon the opposite sides thereof two castings 2 and 45 3, bolted thereto so as to project past the end of the beam in such manner that the outer

ends together form a U-clip. Formed integrally with the casting 3 is a transversely-extending tubular socket 4, adapted to receive the stem of a pole or tongue when it is desired 50 to use such with the plow.

5 designates a clevis-frame rectangular in form, having at each end thereof a transverse tubular socket, designated, respectively, 6 and 7, within the outer one of which is pivotally 55 mounted in the usual manner an end clevis 8, provided with the usual adjusting-holes 8'. The tubular socket at the rear end of the clevis-frame is interrupted, as indicated at 9, and into this interrupted portion is adapted 60 to fit one of the members of a hinge-block 10, which is pivotally held in place by a bolt or pintle 11. The hinge-block is provided with an integral socket member 10', which is pivotally mounted between the arms of the 65 U-clip formed by the ends of the castings 2 and 3. By this arrangement it will be seen that the clevis-frame 5 is attached to the end of the plow-beam to swing upon a joint having, in effect, a universal movement. Upon 70 the upper edge of the clevis-frame 5 is integrally formed an upwardly and rearwardly extending arm or bell-crank 11, having in the end thereof a rod-receiving aperture 12. Upon the side thereof and at the rear end of 75 said clevis-frame is a similar but laterally-extending arm or bell-crank 13, having in its end a rod-receiving aperture 14.

15 and 16 designate, respectively, two segment-castings mounted upon opposite sides of 80 the beam a short distance in the rear of the castings 2 3, each being bowed outwardly to provide a space into which is pivotally mounted, between the inner walls thereof and the sides of the beam, the ends of the levers 17 and 18, respectively, having thereon the usual locking-dogs, as indicated at 19, adapted to engage the teeth of the segment-castings, whereby the levers are held in adjusted positions.

20 and 21 designate, respectively, two connecting-rods connecting the levers 17 and 18, 90 respectively, with the arms 13 and 11 on the

clevis-frame, whereby the latter is moved, by means of the levers 17 and 18, to various positions of adjustment to regulate the line of draft, and thereby the furrow that is being made.

It is obvious from the drawings that the pivotal connection between the rod 21 and the arm 11 is in line with the vertical axis of the clevis-frame and so arranged that movement there-
10 upon is free and easy and that by reason of a pivotal connection between the rod 20 and the lever 17 no obstruction prevents a free and easy movement of the clevis-frame upon its horizontal axis, constituting, in effect, a
15 universal or gimbal joint between the clevis and the plow-beam the various movements of which are controlled and regulated by the hand-levers at the will of the operator. It will thus be seen that the operator may change
20 the line of draft to regulate the furrow by the use of the levers 17 and 18 without stopping the plow, and he is thus enabled to straighten his furrow while the plow is moving and without getting off his seat in case the furrow
25 has from any cause become irregular or to adapt the plow to the line of draft as the conditions of the land over which he is passing demands or in finishing up a land instead of stopping and raising the old form of clevis one or
30 more notches he simply moves the lever 18, thereby giving the plow a heavier bearing on the landside thereof.

We are aware that it is old to provide a vertical pivot attachment to the plow-beam to regulate the lateral movement of the clevis; but in this construction it is necessary to stop the plow and adjust by hand the vertical adjustment to regulate the line of draft of the plow. This objection is completely done away
35 with in the present invention, and all adjustments of the plow can be made from the seat by the operator without stopping the plow and as rapidly as conditions of the land necessitate to keep an even and uniform furrow.

40 While we have herein shown a preferable embodiment of the invention, we do not limit it to the details of construction herein shown

and described, except in so far as such details are made the subject-matter of specific claims.

50 We claim—

1. A draft attachment for a plow, comprising a hinge-block provided with hinge-sockets extending at right angles to each other and hinged through one of said sockets to the plow-beam, a clevis-frame hinged in the other socket in said hinge-block and provided with a pair of arms projecting therefrom at right angles to each other, and means connected to said arms for moving said clevis-frame and locking it in various adjusted positions. 55

2. A draft attachment for a plow, comprising a hinge-clip mounted upon said plow, a hinge-block provided with hinge-sockets extending at right angles to each other and hinged through one of said sockets to said hinge-clip, a clevis-frame hinged to the other socket in said hinge-block and provided with a pair of arms projecting therefrom at right angles to each other, and means connected with said arms for moving said clevis-frame 60 and locking it in a variety of adjusted positions. 70

3. A draft attachment for a plow, comprising a hinge-clip secured to the end of the plow-beam and provided with an integrally-formed pole-attaching socket, a hinge-block provided with a pair of hinge-sockets extending at right angles to each other and hinged to said hinge-clip, a clevis-frame hinged to the other socket in said hinge-block and provided 75 with a pair of arms projecting therefrom at right angles to each other, a pair of hand-levers mounted upon said plow and connected with said arms, whereby to move said clevis-frame into a variety of positions, and means 80 for locking said levers and said clevis-frame in such adjusted positions, substantially as described. 85
